CHESTER A. FRICK, OF MUNCIE, INDIANA, ASSIGNOR TO GLASCOCK BROTHERS MFG. CO.,
OF MUNCIE, INDIANA, A CORPORATION OF INDIANA

BOTTLE DISPENSING REFRIGERATOR

Application filed November 17, 1928. Serial No. 320,187.

My invention relates to improvements in bottle dispensing refrigerators and it is one of the objects of my invention to provide a refrigerator for dispensing bottled beverages which shall be efficient in cooling the beverages, which may be manufactured at a minimum cost and which shall permit of easy access to the bottles to be dispensed.

For the purpose of disclosing my invention 10 I have illustrated one embodiment thereof in the accompanying drawings in which Fig. 1 is a perspective view of a refrigerator embodying my invention; Fig. 2 is a side elevation partly broken away; Fig. 3 is a detail 15 transverse section, Fig. 4 is a detail corner section showing the manner of assembling the outer panels and corner posts and Fig. 5 is a detail partial plan view of the bottle-supporting rack.

20 In the embodiment of the invention illustrated there is provided four corner posts which are extended to form the supporting legs of the refrigerator. Each of these corner posts is formed of an angle iron 1 the free 25 edges of which have inturned lips or flanges 2. Between these corner posts are secured side panel plates 3 which are formed of sheet metal and have their edges turned in to form inturned lips or flanges 4, which lips or 30 flanges mate with the flanges 2 on the corner posts and are secured thereto by means of suitable bolts or rivets 5. The bottom edges of the side panels are inturned to provide 35 horizontally disposed flanges 6 upon which is supported the bottom plate 7. The structure thus formed comprises an outer casing for a preferably rectangular tub 8, the walls of which are spaced apart from the walls of the outer casing. The space between these 40 walls is filled with suitable insulating material which may be ground cork, rock wool or any other desired insulating material. The upper edges of the side walls of the tub 8 are turned outwardly to form outturned flanges 45 9. It will be noted that the top edge of the tub stops short of the top edges of the side panels and this space on each side is filled by an L-shaped filler the bottom horizontal leg 11 of which rests upon and is welded or otherwise secured to the flange 9, while the verti-

cal leg 12 extends parallel with the side panel. This arrangement provides for a sliding track upon which one, 13, of the cover members is adapted to slide. For closing the space between the top edge of the leg 12 and the top edge of the panel members, and providing a top trim I provide an inverted channel 14, the sides of which telescope the leg 12 and top edge of the panel 3 and the inner side of this channel is provided with an inwardly extending flange 15 which provides a support and slide rail for the other 13', slide top or cover. The channels 14 are preferably secured in position by threaded screws extending through the same and through the side 55 panels.

The slide tops or covers 13 and 13' are each formed of suitably dished plates telescoping one another to form a hollow top, the space between the two plates being filled 60 with insulating material.

Arranged to be supported within the tub, below the top thereof, but spaced above the bottom thereof are a plurality of bottle racks, preferably three in number. Each of these 75 racks comprises a plurality of bottom slats 16 connected at their ends to the bottoms 17 of U-shaped straps 18 which form the end members of the racks. These straps at their upper ends are connected together by a cross 80 strap 19 which has suitable spaced apart loops 20 formed therein to constitute handles for the rack. Side straps 21 extend between the side members of the end straps and the slats and side straps are connected together by 85 suitable transverse U-shaped straps 22 intermediate of their ends. Extending between the end members of the rack are spacer bars 23 which divide the rack into three longitudinally extending channels, each adapted 90 to receive the bottles in upright position and maintain the same in a row. Each of the racks is supported upon inturned lugs 24 of flat bars 25 welded or otherwise secured 95 to the opposite ends of the tubs.

In operation the tub is filled with a suitable cooling liquid, preferably clear water, to a point where, when the bottles are supported within the tub in the racks they will be immersed almost to their tops. Within 100

the tub a suitable refrigerant, such for instance as a block of ice, is placed in the water before the racks are inserted in position. When the racks are inserted in position this ice is held by the bottom of the racks submerged beneath the top of the water and beneath the bottom of the bottles so that, the coolest water always surrounds the bottles. When it is desired to serve a bottle, it is merely necessary to slide one or the other cover slides back and remove a bottle from the rack, at the same time inserting a bottle to be cooled in place thereof.

I claim as my invention:

- 18 1. A refrigerator comprising an inner tub substantially rectangular in shape, insulating material covering each of the four side walls of said tub, a metal panel for each of the side walls covering said insulating material, four 20 corner posts comprising angle members arranged at each corner of said structure, the angle members being extended to provide supporting legs therefor, the edges of the panel members being inturned to form flanges 23 and the edges of the angle members being inturned to form mating flanges, and means for connecting said flanges to secure the panels to the legs and form an outer casing for the support of said tub.
- 30 2. A refrigerator comprising an outer casing, a tub arranged within said casing and having its walls spaced apart from the walls of said casing, an insulating filler interposed between the walls of the tub and the casing, 35 the top edge of said tub stopping short of the top edge of the casing, L-shaped filler bars mounted on the top edges of said tub and having their short legs resting on said edges with their long legs extending parallel to the sides of said casing and to the top thereof, whereby a shoulder is formed for the reception of a sliding cover and channel cap bars telescoping said filler bars and panels, each having an inturned flange to 45 form a second track for a sliding cover member above said first track.
3. A refrigerator comprising an inner tub substantially rectangular in shape, insulating material covering each of the four side walls of said tub, a metal panel for each of the side walls covering said insulating material, four corner posts comprising angle members arranged at each corner of the above structure, the angle members being extended 55 to provide supporting legs therefor, a rectangular top member closing the space between the tub and the outer panels and formed of channels, one leg of which overlaps the panels and corner members and the other leg of 60 which overlaps the upper edge of the side walls of the tub.
4. A refrigerator comprising an inner tub substantially rectangular in shape, insulating material covering each of the four side walls 65 of said tub, a metal panel for each of the

side walls covering said insulating material, four corner angles arranged at each corner of the above structure and a rectangular top frame closing the space between the tub and outer panels and formed of channels, one leg of which overlaps the panel and corner angles and the other leg of which overlaps the upper edge of the side walls of the tub.

In witness whereof, I, CHESTER A. FRICK, have hereunto set my hand at Muncie, Indiana, this 30th day of October, A. D. one thousand nine hundred and twenty-eight.

CHESTER A. FRICK.
